CLAIM

The ornamental design for dispensing valve, as shown and described herein.

DESCRIPTION

FIG. 1 is a top, front and right side perspective view of the dispensing valve;

FIG. 2 is a front view thereof, which is identical to the rear view;

FIG. 3 is a right side view thereof, which is identical to the left side view; and,

FIG. 4 is a top view thereof.

The dispensing valve will be generally used as a part of a container. In the drawings, the broken lines depict environmental subject matter only and form no part of the claimed design.
